(57) **CLAIM**

The ornamental design for a bottle, as shown and described.

DESCRIPTION

FIG. 1 is a perspective view of a first embodiment of a bottle embodying the present invention;

FIG. 2 is a front elevational view thereof; and,

FIG. 3 is a perspective view of a second embodiment of a bottle embodying the present invention.

The broken line showing of the environment is for illustrative purposes only and forms no part of the claimed design.

1 Claim, 3 Drawing Sheets

FIG. 1

FIG. 2

FIG. 3

UNITED STATES PATENT AND TRADEMARK OFFICE
CERTIFICATE OF CORRECTION

PATENT NO. : Des. 538,169 S
APPLICATION NO. : 29/225897
DATED : March 13, 2007
INVENTOR(S) : Andreas Nosslbock

Page 1 of 1

It is certified that error appears in the above-identified patent and that said Letters Patent is hereby corrected as shown below:

Title Page, Item (30) Foreign Application Priority Data "Sept. 23, 2002" should be
-- Sept. 23, 2004--.

Signed and Sealed this

Eighth Day of May, 2007

A handwritten signature in black ink, appearing to read "Jon W. Dudas". The signature is written in a cursive style with a large, stylized "J" and "W".

JON W. DUDAS
Director of the United States Patent and Trademark Office
